Assistant Examiner — William B Melliar

(57) **CLAIM**

The ornamental design for a flashlight attachment, as shown and described.

DESCRIPTION

FIG. 1 is a front view of a flashlight attachment showing my new design;

FIG. 2 is a rear view of the flashlight attachment;

FIG. 3 is a right side view of the flashlight attachment;

FIG. 4 is a left side view of the flashlight attachment;

FIG. 5 is a top view of the flashlight attachment;

FIG. 6 is a bottom view of the flashlight attachment; and,

FIG. 7 is a top front side perspective view of the flashlight attachment.

The broken lines in FIG. 7 are illustrative of environmental structure forming no part of the claimed design.

1 Claim, 3 Drawing Sheets
